UNITED STATES PATENT OFFICE

WILLIAM G. ABBOTT, JR., OF MILFORD, NEW HAMPSHIRE

VAPOR PRESSURE APPARATUS

Application filed July 3, 1928. Serial No. 290,174.

This invention relates to apparatus for pumping vapor or the like and more particularly to apparatus of this character which is arranged to maintain a partial vacuum in a vapor duct or ducts, for example in a vapor or steam heating system.

In general the preferred apparatus disclosed herewith comprises a pumping factor of the general type disclosed in my prior

United States Patent No. 1,102,222, which is characterized by a centrifugally maintained liquid ring and fluid pockets rotatable in relation to the ring and diminishing in capacity from the low to the high pressure end of the rotor. Apparatus of this character when arranged in conjunction with vapor pumping means is adapted to utilize a portion of the condensate to form and replenish the liquid annulus, while the latter may aid in effecting the condensation of the vapor.

In certain installations a pump of this character preferably may be combined with a suitable driving factor, such as a steam turbine or motor; the motive vapor for the latter and the pumped vapor may each be condensed within a common compartment and may both join the liquid ring. Thus in one embodiment of my invention illustrated herewith, I provide a driving factor or motor having the same general construction as the pump factor, the common liquid drum for these two factors being contained within a common casing.

When used in a low pressure heating system, apparatus of this character may receive the vapor from the heating coils or radiators, may partially or wholly effect the condensation of the same, and may separate non-condensable gases from the vapor and condensate, exhausting the former to the atmosphere and pumping the condensate to any convenient point, such as the boiler or a supply reservoir for the same. Thus a device of this character may serve not only to maintain a suitable partial vacuum in the heating ducts but may also serve to return the condensate water vapor to the boiler against any suitable pressure, while pumping the non-condensable gases into the air.

The present invention provides means per-

mitting the vapor duct which may have a comparatively large capacity to extend directly into the rotary casing of the pumping factor, and affords means providing an effective seal between the relatively moving casing and duct while avoiding the necessity of using packing, stuffing boxes or similarly troublesome and unsatisfactory arrangements at this point.

A pump of this type may advantageously be arranged so that the axis of rotation of the helical passage is angularly disposed in relation to the axis of rotation of the liquid drum. Such an arrangement permits the passage to have a constant width throughout its length and permits it to have a varying capacity due to its angular relation to the inner surface of the liquid drum, thus avoiding certain of the losses due to movement of the liquid which characterized pumps of this character having a helical passage of diminishing width.

Further aspects of the invention relate to control means arranged in conjunction with condensing and/or pumping apparatus of the preferred character, said control means being adapted to regulate the movement of fluid into or out of the pumping apparatus or being arranged for other suitable purposes.

In the accompanying drawings, which exemplify various structural expressions and adaptations of my invention,

Fig. 1 is a view in central, cross-sectional view of one form of the improved pumping apparatus in combination with a motor factor for driving the same;

Fig. 2 is a central cross-sectional view of another embodiment of the invention which may be provided with any suitable driving means;

Fig. 3 is a similar view showing a somewhat different arrangement of the pumping factor;

Fig. 4 is a central sectional view of still another type of pump arranged in conjunction with control means to regulate the flow of fluid through the apparatus;

Fig. 5 is a top plan view with parts broken away of the assembly shown in Fig. 4; and

Fig. 6 is a section on line 6-6 of Fig. 1.

Referring first to Fig. 1 of the accompanying drawings, the numeral 1 indicates a vapor duct coming from any suitable vapor source, such as heating coils or radiator. This duct 5 may supply vapor and/or condensate to the pumping factor. The latter preferably is arranged within a suitable rotatable casing 2 which also contains an appropriate motor factor. Suitable supports or brackets 3 are 10 arranged adjoining the opposite ends of the casing 2 to support the same. For this purpose one end of the casing may receive a continuation 4 of the vapor pipe 1, a suitable bearing being arranged about this continuation and being connected to the end of casing 15 2. The opposite end of the casing may rotate about a similar hollow trunnion 5. The pipe continuation 4 and the trunnion 5 may each have an annular flange 6 upon its inner end, 20 these flanges being arranged to extend into the inner surface of the centrifugally held liquid body 10 which is maintained adjoining the outer wall of casing 2 when the device is running at its normal speed, and thus permitting 25 the provision of liquid seals at the ends of the outer rotor. The liquid 10 may consist of water, mercury or any suitable liquid.

Eccentrically disposed within the rotatable 30 casing 2 is a hollow shaft 9, which may be supported by suitable brackets 19 that are secured to the trunnion elements 4 and 5 at opposite ends of the casing. A pump rotor 12 may be mounted upon the shaft 9, being 35 arranged to cooperate with the liquid ring in forming fluid pockets. This rotor carries a helical flange 15, the pitch of this flange gradually decreasing from the low pressure end adjoining the pipe 4 to its opposite end. The 40 diameter of the rotor 12 preferably is greater at its high pressure end.

The edge of the flange is submerged in the centrifugally held liquid body 10, while the eccentric arrangement of rotor 12 in relation 45 to this body permits a portion of each convolution of the helical passage to be immersed in the liquid so that, in effect, a plurality of liquid pistons are provided which separate the passage into a series of crescent-shaped 50 pockets or, in other words the liquid occupies a portion of each convolution of the helix. As shown in Fig. 6 the entering end of flange 15 traps a body of fluid at the low pressure end of the rotor; due to the gradual constriction 55 of the helical passage, this fluid is compressed as it passes into the high pressure chamber at the large end of the rotor or drum 12. The tapered form of the latter permits the edge of each convolution of the 60 helical flange to be immersed to substantially the same extent in the liquid body, although the latter may be distorted somewhat at the high pressure end of the pumping factor due to the pressure of the trapped fluid.

Disposed between member 12 and the flange

6 is a suitable condensing instrumentality 17. A water pipe 18 enters the side of trunnion member 4 and is connected to the end of hollow shaft 9. Suitable jet openings 18^a are arranged about the surface of member 17, these orifices being connected with the passageway within shaft 9 so that water may be cast outwardly from the same due to the hydrostatic pressure acting through pipe 18 and to the action of centrifugal force. 70

Upon the intermediate portion of shaft 9 I preferably arrange a rotatable partition plate 20, the periphery of which preferably engages the inner surface of the liquid annulus 10. A suitable outlet pipe 21 within shaft 80 9 is adapted to receive non-condensable gases from the compression chamber which is located between the partition plate 20 and the adjoining portion of the rotor 12. Pipe 21 extends through the end of shaft 9 which is 85 carried in trunnion 5, thus being adapted to exhaust non-condensable gases to the atmosphere. 95

A suitable motor factor is arranged within casing 3 between partition plate 20 and the trunnion 5. This factor may be driven by steam or vapor entering through the pipe 37 which is arranged to vent fluid into the hollow trunnion 5. The steam or propellant fluid which is received in pipe 37 may come 95 from a separate source of steam, may come from the same boiler which supplies the vapor entering pipe 1, or may come from a portion of the vapor duct in advance of the outlet into the pumping factor. The motor factor 100 preferably is provided with a rotary drum 32 which is carried upon shaft 9. Arranged upon this rotor is a helical flange 33, the pitch of this helical member gradually increasing 105 from its high pressure end adjoining the trunnion 5 toward the opposite end. This 110 flange and the helical passage defined thereby is opposite in pitch to that of the helical passage about rotor 12, the general design of these rotors may be similar however, the exact dimensions and proportions of each being 115 varied to suit the initial and final pressure of the motor and pumped fluids which pass through the apparatus. Adjoining the low pressure end of rotor 32, I may provide a condensing instrumentality 37 of the same general type as the instrumentality 17, the water for the second condensing means also being received from the pipe 18 through the hollow shaft 9. A pipe 15 may extend from the plate 120 20 to the low pressure end of rotor 12, thus permitting the movement of non-condensable gases from the outlet chamber of the motor factor to the inlet chamber of the pump factor, whence they may be exhausted to the air. 125

Rotor 32 carries a gear 44 which meshes with an internal gear 46 within casing 2 whereby the drum imparts rotative movement to the casing. A guard plate 47 is secured to the casing 2 adjoining gear 46 and is 130

adapted to aid in permitting the retention of lubricant about the gears. Suitable openings 49 are provided in the extension of rotor 32 between gear 44 and the body portion thereof to permit steam to enter the high pressure chamber and thus to pass into the helical passage.

In the operation of apparatus of the type disclosed in Fig. 1 steam or vapor entering pipe 37 is received by the helical passage upon rotor 32 and is caught in one of the crescent-shaped pockets which are defined by the helical flange and the liquid drum. Due to the tapered arrangement of the helical passage upon the drum, the tendency of the propellant vapor to expand causes the same to effect the gradual enlargement of each of the crescent-shaped pockets, thus causing rotation of the drum 32 and the shaft 9. Rotation of the latter obviously results in a similar movement of the rotor 12. Rotation of outer casing 2 at a fairly high speed is effective in maintaining the liquid annulus 10 in position under the action of centrifugal force.

Vapor entering through pipe 1 passes into the low pressure chamber about condensing instrumentality 17 contacting with the whirling surface of liquid body 10 and being cooled by the water jets from the condensing factor. Thus condensation of some or all of the vapor may be effected. The rotating member 12 with its helical flange 15 is adapted to receive crescent-like pockets of fluid at low pressure from the inlet chamber and to effect the gradual compression of the same due to the gradually diminishing capacity of the helical passage. Thus any vapor which has not already been liquefied is condensed due to the increase in pressure and the concomitant cooling by the liquid body 10, while the pressure of the non-condensable gases is increased so that these gases may leave the pumping member 12 at a pressure which is at or slightly above atmospheric. These gases are exhausted through outlet pipe 21.

A suitable scoop 40 projects into an annular extension of the casing 2 which is connected to the interior of the same by suitable passageways. This scoop is formed by one end of a water return pipe 42. Thus rotation of the liquid body at high speed results in the impelling of water into the pipe 42 under considerable pressure due to the rotational momentum of the liquid body and due to the effect of centrifugal force. The steam which passes through the helical passage upon rotor 32 gives up its energy in rotating the latter, passing into the condensing chamber between this rotor and partition plate 20. The condensing factor 37 there cooperates with the liquid drum 10 in liquefying the steam and causing the same to be added to the liquid drum. Similarly the water supplied to the condensing factors is ultimately collected by the liquid body and passes outwardly through

pipe 42 which may be connected to the supply reservoir for the boiler or may be connected to any suitable drain.

Obviously any suitable starting means such as a belt engaging the annular extension 45 upon casing 1 may be utilized to start the combined motor and pump shown in Fig. 1. As soon as the liquid ring 10 is formed due to rotation of casing 3 and the action of centrifugal force, the starting motor may be disconnected. Thereupon the steam pockets will be formed in the helical passage about drum 32 and the steam entering pipe 31 will cause continued rotation of the two rotors and their common shaft in response to the initial rotation of the liquid body 10.

Fig. 2 illustrates a combined condensing factor and vapor pump which is adapted to be driven from any suitable source of power through the shaft 50. This apparatus is provided with an outer casing 51 in which the rotatable casing 52 is located. The vapor pipe 53 terminates within one end of casing 52 being loosely received in an outstanding annular flange 55 upon the end of the casing. The opposite end of casing 52 is provided with a hollow extension 54 which is mounted upon bearings 56 carried by an extension 57 of the outer housing 51. The shaft 50 preferably extends inwardly through the housing extension 57 and the casing extension 55, being supported by a bearing 59 in the former and by a bearing 60 which is supported by a suitable spider 61 located in the open end of pipe 53. Shaft 50 carries a drum or rotor 64 which is rotatably mounted within housing 52. This rotor may be of the general type previously described and disclosed in my prior Patent No. 1,102,222 carrying a helical flange 65, the pitch of which gradually decreases toward its high pressure end. It is thus evident that the helical flange defines a helical passage of gradually diminishing capacity. The outer edge of the flange preferably carries a plurality of blades 66 which are secured to the flange in any suitable manner.

A body of suitable liquid 70 is located within the housing 52, being maintained in place by centrifugal force and forming a liquid annulus when the rotors are turning. This annulus is so arranged in relation to the rotor and the flange thereon that the outer edge of the flange is constantly immersed in the liquid, the rotational axis of drum 64 being eccentrically disposed in relation to the axis of casing 52 in such a manner that a portion of each convolution of the helical passage is submerged in or occupied by the liquid body while another portion of each passage provides a crescent-shaped fluid pocket.

A water supply pipe 75 extends into the vapor pipe 53 and has a continuation provided by a hollow end portion of the shaft 50 which is in telescoping engagement with this

water pipe. A condensing factor 71 is carried by shaft 50, this factor being located adjoining the open end of vapor pipe 53 and being adapted to project a plurality of jets of cooling water into the low pressure chamber. Disposed within the outer housing 51 is a suitable annular trough 76 which has an outlet pipe 77 at the bottom of housing 51. Segmental openings 78 in the end of casing 52 communicate with an annular extension 79 of the casing, the latter having an out-turned portion received within the annular trough 76, water under centrifugal force accordingly will be cast outwardly into the trough and pass into pipe 77 under considerable pressure. Radially disposed blades 73 may be located in the extension 79 to aid in attaining this result.

The shaft 50 preferably carries an annular plate 81 spaced from the larger end of rotor 64 and providing a high pressure chamber communicating with the outlet end of the helical passage, it being understood that the periphery of this plate engages the rotating liquid body 70 which provides a seal about the edge of the plate. A suitable duct 80 is formed in the shaft 50, being adapted to receive the non-condensable gases from the high pressure chamber and to exhaust the same to the atmosphere. Suitable packing may be arranged around the portion of shaft 50 which extends through the end of casing extension 57. The arrangement of the duct 80, housing 51 and vapor duct 53 in this manner permits the vapor duct to extend into the housing, which is rapidly moving in relation to the same, without requiring the necessity of special packing or the like about the comparatively large vapor duct and yet avoiding undesirable leakage of atmospheric air into the low pressure portion of the apparatus. It is evident that the duct 53 is secured firmly to the wall of the fixed housing 51 and that the flange 55 of the rotatable casing 52 is arranged loosely about the inner end of the duct. The opening between flange 55 and the end of the duct communicates with the interior of chamber 51 and with the low pressure portion of the pump factor, so that a low pressure is maintained within the interior of chamber 51. Consequently, any liquid which may leak into the same or which may pass into the same in the form of vapor and there condense tends to be vaporized, due to the suction received from the pumping element. When thus vaporized, it is drawn to the interior of casing 52. Thus, I have provided means permitting a large vapor duct or the like to extend into a rotary pump casing and forming a substantially air-tight joint between the same without the necessity of complicated and troublesome packing, stuffing boxes or the like.

In the operation of a device of this character the shaft 50, being driven from any

suitable source of power, serves to rotate drum 64 and condensing factor 71 at comparatively high speed. As a consequence of this action the blades 66 upon the rotor cause liquid body 70 to rotate and to assume an annular form as illustrated. The rotary movement of this liquid body also tends to impart a rotary movement to the outer casing 52 which is supported upon anti-friction bearings 56. Vapor entering through pipe 53 passes into the low pressure chamber about factor 71 and is cooled by the spray jets issuing from that factor, the whirling of this member tending to aid the movement of the water outward due to the action of centrifugal force and the whirling of the liquid body 70 tending to give a similar movement to the vapor, thus causing the same to be brought into contact with the surface of the cooling water. As a consequence a large portion or all of the vapor is condensed and collected by the liquid annulus 70.

Any vapor which is not condensed in the low pressure chamber is caught in the helical passage provided by drum 64 and is there compressed due to the gradually diminishing capacity of that passage and the contact with the liquid 70. Any non-condensable gases which may have been mixed with the vapor are trapped in the helical passage and are there compressed, being raised to atmospheric pressure or to a pressure slightly above the same and being exhausted into the atmosphere through passage 80.

Since the liquid body 70 is constantly tending to increase in volume due to the condensate added thereto and due to the water issuing from the jets of factor 71, it is necessary to provide means to maintain this body at a given volume and to remove the excess water. For this purpose I have provided the openings 78 and the annular member 79, the former being adapted to cast water outwardly into trough 76 whence it passes into pipe 77.

It is therefore evident that a device of this type is adapted to receive ordinary vapor, i. e., true vapor mixed with non-condensable gases, to cause or maintain a low pressure within the vapor duct while exhausting the non-condensable gases at atmospheric pressure, to liquefy the vapor which has not already condensed and to pump the condensate out through pipe 77 at a suitable pressure.

Fig. 3 is a view of a slightly different embodiment of the invention which is also provided with an outer housing 90 which contains an inner rotatable casing or rotor 91, the latter having an extension 92 mounted upon bearings 94 which are located in a corresponding extension 95 of the outer housing. A suitable vapor duct 96 extends into the casing 91. The shaft 100 which carries the inner rotor 101 is located at an angle to the

axis of rotation of casing 91, i. e., preferably inclined at an angle to the horizontal.

The rotor may be provided with a suitable helical flange 102 which in this form of the invention may have a constant pitch from the small to the large end of the drum. Suitable bearings 109 support the shaft 100 in its angular position and gearing 110 may be arranged between the shaft to the casing 10 tension 92 to impart rotary movement from the former to the latter. A suitable liquid body 114 is normally disposed within casing 91 and is adapted to form a liquid annulus or ring when the casing is rotated at high speed. A condensing factor 71 is adapted to receive cooling water from pipe 75 in the same general manner as described above with reference to the apparatus shown in Fig. 2. In this form of the invention suitable openings 116 are arranged at the high pressure end of casing 91 and are adapted to emit fluid to the annular trough 117 which is located upon the end of the outer rotor. A scoop 118 formed by the end of the pipe 119 is adapted to engage liquid carried by the trough 117. A suitable gas outlet 80a communicates with the high pressure chamber in the same general manner as described in the reference to Fig. 2.

In the operation of the apparatus shown in Fig. 3 rotation is imparted to the shaft 100 and thence to rotor 102 and condensing factor 71, while the gearing 110 also causes the housing 91 to rotate at a suitable speed. The rotor 101 preferably is so arranged in relation to the centrifugally held body of liquid 114 that one portion of each of the convolutions of the helical passage is occupied by the liquid body, as indicated at the top of the rotor in Fig. 3, while suitable crescent-shaped pockets are provided by each of the convolutions. In this form of the invention, due to the angular disposition of the axis of rotor 101 in relation to rotor 91, the depth of these pockets gradually decreases toward the outlet end of the helical passage. Thus, movement of fluid along the helical passage results in the compression of the same due to the construction of the passage resulting from the angular arrangement of the inner wall of the same in relation to the liquid drum. As a consequence a spiral flange of constant pitch may be utilized to provide a helical passage of gradually diminishing volumetric capacity, such an arrangement avoiding certain fluid losses which are present with the type of rotor shown in Fig. 2, since the tendency of the constructed portion of the passage to squeeze out the liquid from between convolutions of the helical flange is avoided in this form of the invention.

Vapor entering through pipe 96 is largely condensed by the action of the spray from factor 71 and contact with the whirling of

liquid body 114, while non-condensable gases are caught by the entering end of flange 102 and are compressed in the crescent-shaped pockets provided by the helical passage and the liquid drum. Thus the non-condensable gases reach the high pressure chamber at or slightly above atmospheric pressure and are exhausted to the atmosphere through passage 92 and opening 80a. The liquid body 114 is constantly receiving the condensate and the water from factor 71. Consequently the scoop 118 is arranged to project into the surface of the centrifugally held liquid body under conditions approximating atmospheric pressure. The centrifugal force and the momentum of the liquid tend to cast the same into pipe 119 under considerable pressure so that the liquid may be returned to the boiler or the feed water tank which is in turn connected to the boiler.

The shaft 100 preferably carries disk 81a, similar to the disk 81 of Fig. 2, and is also provided with an air passage 80a connecting the high-pressure chamber between the end of the rotor and the disk with the atmosphere.

It is thus evident that in this form of the invention the vapor is condensed while a suitable vacuum or low pressure is maintained within duct 96 and the piping connected thereto. The condensate as well as the cooling water for the condensing factor is pumped outwardly into pipe 119, while the pressure of the non-condensable gases is raised to such a point that they may be exhausted to the atmosphere.

While I have illustrated the use of condensing factors 71 in conjunction with the embodiments of my invention heretofore described, it is to be understood that the use of such a factor is optional. In certain cases apparatus of this character may be arranged to receive a mixture of vapor and condensate or merely to receive the condensate and/or non-condensable gases from a suitable condenser.

Fig. 4 illustrates a further variation of my invention wherein the rotatable factor may turn about a vertical axis. In this form of the invention I provide a fixed outer casing 140, the bottom of which is closed and the top of which is connected to the vapor pipe 141. A suitable hollow shaft 142 extends upwardly through the top of the casing and its connection to the vapor pipe, this shaft being rotated by the driving belt 144 or any suitable means. The lower end of the shaft preferably is supported by a thrust and radial bearing 145 at the bottom of casing 140. This shaft may carry a rotor 146 with blades 147 corresponding to the construction previously described with reference to rotor 64 and blades 66 of Fig. 2, the larger, high pressure end of rotor 146 obviously being located adjoining the bottom of casing

140. A gas outlet opening 150 is arranged in the wall of the hollow shaft 142 between the lower end of rotor 146 and bearing 145. A water outlet pipe 149 is connected with the bottom of housing 140, this pipe being controlled by a valve 151 which is operated by a spindle 152. The latter may be provided with means for manual control, if desired, but preferably is connected to the automatic control means illustrated herewith. For this purpose a suitable light, cupped element 155 is mounted upon a vertically disposed pivot 156; the end of the latter is connected to a suitable arm 158 that in turn is connected to the link 157, the latter being articulated to the outstanding arm 159 upon spindle 152. A spring 165 or other yieldable means normally tends to hold the valve closed and to hold member 155 against the liquid surface.

In the operation of the apparatus shown in Figs. 4 and 5, the shaft 142 is driven by belt 144, causing the rotation of the rotor 146 with the blades 147, the latter imparting a whirling motion to the liquid body 160, causing the same to assume an annular form within casing 140. Vapor entering through pipe 141 passes downwardly into the center of the liquid annulus contacting with the surface of the whirling liquid and condensing. Fluid which is not thus condensed, including non-condensable gases, is caught by the flange 148 on rotor 146 and is thereby compressed in the same general manner as previously described. Vapor not previously liquefied is condensed while passing through the helical passageway due to the increase in pressure and the exposure to the whirling liquid body 160. The non-condensable gases, having their pressure raised at least as high as atmospheric, pass into opening 150 and then through hollow shaft 142 to the atmosphere. In the meantime the liquid body 160, which is constantly tending to increase in volume due to the accretions from the condensed vapor, is kept substantially constant in volume due to the control factor 155, this factor being arranged to move inwardly when the inner surface of the liquid body 160 moves inwardly due to an increase in the volume of the same; this movement results in the opening of valve 151 and the forcing of water through pipe 149 to the boiler or any suitable point under the artificial liquid head resulting from centrifugal force. On the other hand, movement of the control element 155 outwardly due to the reduction in volume of the liquid body results in the closing of the valve.

Due to the arrangement of the control element 155 at the top of the casing 140, momentary stopping of the rotor will cause the liquid to fall from this element permitting the spring 165 to be effective in closing the valve 151. Thus, in effect, a check valve is provided to prevent a reduction in the pres-

sure within pipe 149 when the artificial liquid head is removed. While, for purposes of convenience of illustration, I have shown this automatic control means in conjunction with a unit having a vertical axis of rotation, it is evident that similar means may be arranged in conjunction with the other embodiments of my invention. For example, when control means of this character is utilized with rotating liquid drums having a substantially horizontal axis of rotation, it may be desirable to provide a separate check valve in the water outlet pipe corresponding to pipe 149 of Fig. 4. It is further evident that control means of this character may be arranged to govern the inflow of liquid to the pump, for example, being connected to a suitable valve in the pipe 75, Fig. 3, which supplies water to the condensing factor. It is further evident that control means of this character may be connected to any other suitable instrumentality which may desirably be governed in accordance with the condition of the liquid drum.

While Fig. 1 illustrates a motor element comprising a drum with a spiral flange thereon, it is evident that a conventional steam turbine might be similarly arranged so that its condensate is added to the liquid drum. Such a turbine could be arranged in the same casing as the drum, or the motor drum or steam turbine might be disposed in a separate compartment or casing and arranged to transmit its condensate to the liquid drum within the pump casing or to the water outlet pipe leading from the same.

It is evident that apparatus of the character disclosed herein is adapted to receive vapor and/or condensate from any suitable source of vapor supply and to effect the condensation of the vapor which has not yet liquefied, pumping the resulting liquid together with any cooling water under a suitable artificial head to any suitable point of use, such as a boiler or the like. Furthermore, this pumping means is adapted to maintain a suitable low pressure in the vapor line, and to this end to remove non-condensable gases from the vapor and to exhaust the same to the atmosphere.

It will be further noted that I have provided means permitting a large vapor pipe to extend into the rotary pump casing and providing a suitable seal about the same without the necessity of arranging packing between the pipe and rotating casing or drum. Thus, as shown in Figs. 2 and 3, the outer stationary casings 51 and 90 are arranged to permit any liquid which may leak into the same to be evaporated and to be drawn by suction to the condensing chamber, or, as shown in Fig. 1, a suitable annular flange may be arranged at the end of the vapor pipe so that its edge projects into the rotating liquid drum which provides a

liquid seal about the same. It is thus evident that the latter arrangement is particularly advantageous when the outer stationary casing is omitted.

5 While, for convenience and clarity of illustration, I have illustrated only a few of the possible combinations of novel factors which are disclosed herein, it is obvious that these factors may be combined with each other in 10 various other ways in accordance with the general principles of this invention.

I claim:

1. In a system of the class described, a casing, a rotary pumping element in the 15 casing, a duct adapted to emit vapor and gas into the casing, condensing means within the casing between the pumping element and the duct, said pumping element being arranged to receive vapor and gas from the condensing 20 means, to condense the former, to compress the gas, and to separate the gas and liquid and separately to exhaust the same.

2. In a system of the class described, a vapor-supply duct, a pump, said pump including 25 a casing containing liquid, the latter being associated with rotary means whereby a liquid ring is formed within the casing substantially from said duct to said pump under the action of centrifugal force, said ring being effective in condensing the vapor passing toward said pump and causing separation of non-condensable gases therefrom, and other parts of the pump cooperating with the ring to compress the 30 gases, said pump having separate outlets for the condensate and the gases.

3. In a system of the class described, a vapor supply duct, a pump, said pump including 35 a casing containing liquid, the latter being associated with rotary means whereby a liquid ring is formed within the casing between said duct and said pump under the action of centrifugal force, said ring being effective in condensing vapor passing into the casing and causing separation of non-condensable gases therefrom, and other parts of the pump cooperating with the ring to compress the gases, the liquid of said ring being replenished by the condensed vapor, and 40 liquid exhausting means designed to receive excess liquid from said ring.

4. In a system of the class described, a vapor supply duct, a pump at the end of said duct, said pump including a casing containing 45 liquid, the latter being associated with rotary means normally to form a liquid ring within the casing under the action of centrifugal force, said ring being effective in condensing the vapor and separating non-condensable gases therefrom, other parts of the pump cooperating with the ring to compress the gases, the liquid of said ring being replenished from the vapor supply, and liquid exhausting means designed to receive 50 excess water from said ring, valve means controlling the flow of liquid from the ring, and control means responsive to the thickness of the ring and governing said valve means.

5. In a system of the class described, a vapor supply duct, a pump at the end of said duct, said pump including a casing containing liquid, the latter being associated with rotary means whereby a liquid ring is formed within the casing under the action of centrifugal force, said ring being effective in condensing the vapor and causing separation of non-condensable gases therefrom, other parts of the pump cooperating with the ring to compress the gases, the liquid of said ring being replenished by the condensed vapor, and liquid exhausting means designed to receive excess liquid from said ring, valve means controlling the flow of liquid from the ring, and control means responsive to the thickness of the ring and governing said valve means.

5. In a system of the class described, a vapor supply duct, a pump at the end of said duct, said pump including a casing containing liquid, the latter being associated with rotary means whereby a liquid ring is formed within the casing under the action of centrifugal force, said ring being effective in condensing the vapor and causing separation of non-condensable gases therefrom, other parts of the pump cooperating with the ring to compress the gases, the liquid of said ring being replenished by the condensed vapor, and liquid exhausting means designed to receive excess liquid from said ring, valve means controlling the flow of liquid from the ring, and control means responsive to the thickness of the ring and governing said valve means, said control means comprising a movable member adapted to be held against the inner surface of the liquid ring, and linkage imparting movement from said member to the valve.

6. In a system of the class described, a vapor duct, a casing about the end of said duct, a rotary pumping element within the casing, means within said casing for supplying water jets to the casing whereby condensation of vapor from the duct may be effected, and means for removing the water and condensate from the casing.

7. In combination, a hollow outer casing containing a body of liquid, means to maintain said liquid in position by centrifugal force, a drum having a helical passage partially submerged in said centrifugally held liquid body, an inlet chamber and an outlet chamber communicating with the ends of the passage, the latter diminishing in effective size from its low to its high pressure end, and means to effect relative rotation of the passage and liquid body, a liquid duct communicating with the liquid drum, a valve controlling flow through said duct, and means controlled by the position of the liquid in the body to regulate said valve.

8. In combination, a hollow outer casing containing a body of liquid, means to maintain said liquid in position by centrifugal force, a liquid duct extending into the casing, a valve controlling flow through the same to regulate the volume of the centrifugally held liquid body, an inner member movable in relation to the liquid body and co-operating therewith to provide fluid pockets, the latter diminishing in effective size from the low to the high pressure end of the inner member, a movable member yieldably held against the inner surface of the centrifugally held liquid, linkage connecting the member to the valve, movement of said member in response to variation in amount of centrifugally held liquid serving to control

liquid flow through the duct and thus keeping the amount of centrifugally held liquid constant.

9. In combination, a hollow outer casing containing a body of liquid, means to maintain said liquid in position by centrifugal force, an inner member movable in relation to the liquid body and co-operating therewith to provide fluid pockets, the latter diminishing in effective size from the low to the high pressure end of the inner member, and means to effect relative movement of the liquid body and drum, a regulating member operated by the condition of the centrifugally held liquid for maintaining an adequate supply thereof, said member being held yieldably upon the inner surface of the same, and being connected to exterior control means.
10. In a system of the class described, means to maintain an annular body of liquid under centrifugal pressure and a rotor having a helical passage on an axis eccentric to the axis of said annular body, whereby the intercept of liquid and helical passage is occupied by a series of liquid pistons movable with respect to said passage, a vapor duct having an outlet arranged to emit vapor within said annular body at a point spaced axially from the helical passage whereby the vapor may be given a whirling action and condense due to contact with the annular body while non-condensing gases carried by the vapor may be caught between liquid pistons in the helical passage, said passage having a gradually diminishing cross-sectional capacity whereby the gases may be condensed, and outlet passages to exhaust said gases to the air and to maintain said liquid body at a substantially constant volume.
11. In combination, a pump factor and a motor factor, a common casing enclosing both of said factors, means for utilizing centrifugal force for maintaining a liquid annulus in said casing, each of said factors comprising a drum having a helical passage partially submerged in said centrifugally held annulus, each of said helical passages connecting with an inlet chamber and an outlet chamber, the pump passage gradually diminishing in size from its high pressure end to its low pressure end, the motor passage gradually increasing in size from its inlet to its exhaust end, and means to effect a relative rotative movement between each of the drums and the liquid annulus.

12. In combination, a pump factor and a motor factor, a shaft connecting the same, a common casing enclosing both of said factors, means for utilizing centrifugal force for maintaining a liquid annulus in said casing, each of said factors comprising a drum having a helical passage partially submerged in said centrifugally held annulus, each of said helical passages connecting with an inlet chamber and an outlet chamber, the pump

passage gradually diminishing in size from its high pressure end to its low pressure end, the motor passage gradually increasing in size from its inlet to its exhaust end, means to effect a relative rotative movement between each of the drums and the liquid annulus, said pump factor being arranged to receive vapor and to compress and condense the same, the motor factor being adapted to receive vapor under pressure, and means associated therewith to condense the same, the factors being arranged to add the condensate to the liquid annulus, and means for draining surplus liquid from the latter.

13. In a system of the class described, the combination of means for establishing and maintaining a liquid annulus, means for delivering vapor within one end of the annulus, means within the annulus for condensing vapor so delivered, and means within the annulus and cooperating therewith for withdrawing uncondensed gases therefrom.

14. In a system of the class described, the combination of means for establishing and maintaining a liquid annulus, means for delivering vapor within one end of the annulus, means within the annulus and adjacent the latter end thereof for projecting jets of condensing fluid into the entering vapor, and means within the annulus and cooperating therewith for translating uncondensed gases to the other end thereof.

15. Liquid pumping means comprising a casing, a duct for delivering fluid to the said casing, means arranged to form a liquid ring in the casing under the action of centrifugal force, means within the casing to cooperate with the liquid ring for pumping fluid delivered by said duct, an annular trough extending about the casing for receiving liquid from the liquid ring, a scoop within said trough and a pipe forming a continuation of said scoop, whereby the liquid is forced into the pipe under an artificial head, due to the action of centrifugal force.

16. In a system of the class described, means to maintain an annular body of liquid under centrifugal pressure and a rotor having a helical passage on an axis eccentric to the axis of said annular body, whereby the intercept of liquid and helical passage is occupied by a series of liquid pistons movable with respect to said passage, a vapor duct having an outlet arranged to emit vapor within said annular body at a point spaced axially from the helical passage whereby the vapor may be given a whirling action and condense due to contact with the annular body while non-condensing gases carried by the vapor may be caught between liquid pistons in the helical passage, said passage having a gradually diminishing cross-sectional capacity whereby the gases may be condensed, and an outlet passage to exhaust said gases to the air, a liquid outlet means arranged to maintain

5 said liquid body at a substantially constant volume, said outlet means comprising an annular trough adapted to receive overflow from the liquid body, and an outlet pipe, said trough being adapted to deliver liquid to said pipe under an artificial head resulting from centrifugal pressure of the liquid in the trough.

10 17. Apparatus of the class described comprising a hollow outer casing containing a body of liquid, means to rotate said liquid to maintain it in place by centrifugal force, a drum having a helical passage partially submerged in said liquid, the unsubmerged portions of the passage forming successive fluid 15 pockets, said drum being rotatable about an axis inclined in relation to the axis of rotation of the liquid body, the inner wall of successive pocket portions of the helical passage 20 thus being disposed at different distances from the inner surface of the liquid body, whereby the effective capacities of the portions of the fluid pockets may diminish toward one end thereof.

25 Signed by me at Milford, N. H., this 29th day of June 1928.
